UNITED STATES PATENT OFFICE.

LEE HOWARD SIMMONS, OF GOLDSBORO, NORTH CAROLINA, ASSIGNOR TO SIMMONS
FORCED DRAFT COMPANY, A CORPORATION OF NORTH CAROLINA.

FORCED-DRAFT FURNACE-GRAVE.

1,270,065.

Specification of Letters Patent. Patented June 18, 1918.

Application filed January 30, 1917, Serial No. 145,442. Renewed April 29, 1918. Serial No. 231,536.

To all whom it may concern:

Be it known that I, LEE HOWARD SIMMONS, a citizen of the United States, residing at Goldsboro, in the county of Wayne and State of North Carolina, have invented certain new and useful Improvements in Forced-Draft Furnace-Grates, of which the following is a specification.

My invention relates to a new and useful improvement in grates and especially to that class known as forced draft furnace grates.

The present invention also relates to certain improvements on that type of grates for which a patent was granted to me on April 4, 1916, and being numbered 1,178,274.

This invention, broadly speaking, is similar to the former one in so far that it consists of a number or plurality of hollow grate bars, a manifold disposed transversely of the same, an engine and fan and air ducts leading to said manifold to supply air under pressure thereto, which in turn is supplied to the grate bars and passes therethrough to the fire bed. Also the grate bars at the sides 25 of said grate extend above the level of the fire bed so that the air may be delivered above the normal level of the grate. The bottoms of the grate bars may be swung so that the ashes may be released from them.

This grate like my former one is particularly intended to receive fuel in a finely divided state, although it is to be understood that the larger form of fuel may be advantageously burned. The bed presents a surface in which there are small openings for the passage of air, which openings are so small that little or no fuel will drop therethrough. However, to remove any ashes and dust that sift through these openings, means 35 are provided for simultaneously clearing the inside of the grate bars, so that the said bars will not become choked or clogged, and thereby interfere with the draft.

It is necessary in a grate of this type that the forced air draft reach all the grate bars and be distributed thereto as the heat at the top of the bars is very high, so that I provide a manifold on which one end of each bar rests, said bars having an opening registering with an opening in said manifold. Again, as in the former case, a grate is provided in which the bars positioned at the side are of a different construction than

those shown in the central portion and in which the air spaces are not only provided at the top surface as in the other bars, but also in the inclined surface, so that the forced draft besides entering below the fire bed, will also be shot across the surface of the fire to readily mix with the gases of combustion and in this manner assist them to consume a goodly portion of the smoke which would otherwise be emitted from the chimney; and in many instances will do away with the necessity of a smoke consumer.

So far my present invention is similar to my previous one mentioned, but from here the invention differs as will be plainly seen.

Instead of having a grate bar having a solid integral top surface with air openings as in my former construction, I have a plurality of what I term for convenience, fire bars, to distinguish them from the main grate bars. These fire bars have lugs at their side so that a small space or opening is left between adjacent fire bars for the passage of air. Again, means are provided not only for tilting the bottoms of the grate bars as before, but also for the rocking of the fire bars.

Therefore an object of my present invention is to provide a grate consisting of a plurality of grate bars, the number depending on the desired heating area, a manifold and a plurality of fire bars in said grate bars.

Another object is to provide a grate comprising a plurality of hollow grate bars having independent fire bars located in said grate bars, bottoms pivoted in said grate bars and means for tilting the bottoms and also for rocking the fire bars in said grate bars and simultaneously one with the other.

Still another object of my invention is to so construct the fire bars that they extend transversely of said grate bars making them easier to cast and handle when installing or renewing.

Another object of my invention is to so construct said bottoms of said grate bars that when swung or tilted they will contact with all of the said fire bars in their respective grate bars.

Still another object is to construct the said fire bars so that portions extend down into said grate bars making it necessary to

move the pivotal bottom through a lesser arc, also to construct the fire bars that are situated at the side of the grate in a certain particular manner.

5 Still another object is to provide a manifold having a pivotal bottom formed of two parts thereby making room for the main rock shaft, and the said manifold having air intakes at its opposite ends so that plenty 10 of air will be supplied at all times to the various grate bars. By providing a pivotal bottom in the manifold any ashes or dust that may have gotten in there may be released by moving a handle at the front of the 15 grate connecting with the said pivotal bottoms.

Still another object is to provide a grate of the type mentioned that may be readily assembled, easily installed, capable of using 20 as many units as desired; replacing for any reason new fire bars, to be used in said grate bars; and also provide means in a forced draft furnace grate for rocking the fire bars in said grate.

25 With these and other objects in view my invention consists of certain new and novel features of construction and combinations of parts as will be hereafter more fully described and pointed out in the claims.

30 Referring now to the drawing forming a part hereof, and in which like letters of reference denote similar parts,

Figure 1 is a top plan view partly in section and partly diagrammatic of my improved grate and force draft apparatus.

35 Fig. 2 is an end elevation, partly in section of the improved grate.

Fig. 3 is a side elevation partly in section of the same.

40 Fig. 4 is a sectional view of one of the grate bars showing the pivotal bottom tilted and a fire bar raised by said pivotal bottom.

Fig. 5 is also a sectional view of a grate bar showing one end and the bearing for a 45 pinion of the pivotal bottom.

Fig. 6 is a top plan view of a grate bar with the bottom removed.

Fig. 7 is a longitudinal section of the grate bar showing both bearings for the 50 pinions of the pivotal bottom.

Fig. 8 is a top plan of the pivotal bottom of the grate bar.

Fig. 9 is a side elevation of the same.

Fig. 10 is a top plan of the manifold.

55 Fig. 11 is a side elevation of the same, being broken away in one place for the sake of clearness.

Fig. 12 is a bottom plan of the same with the pivotal bottoms removed.

60 Fig. 13 shows the pivotal bottom used in the manifold.

Fig. 14 shows a side elevation of the same.

Fig. 15 shows a detail of the same.

65 Fig. 16 shows a rod or handle connected to the pivotal bottoms in said manifold.

Fig. 17 is a plan view of the rod or handle.

Fig. 18 shows different details of one of the fire bars.

Fig. 19 is a similar view but in this instance showing one of the fire bars that are 70 situated in the side grate bars.

Referring now to the drawings and for the present to Fig. 1, it will be seen that my improved grate as installed comprises any form of engine or motor power 1, which is 75 connected to a fan or blower 2, from which leads the main air duct 3, from which in turn lead the ducts 4 and 5, the ends of which register with two supports 7 properly set in a foundation for the furnace grate.

80 Resting on the supports 7 which are hollow, and registering with the same is a manifold 8 provided at its top with a plurality of openings 9. This manifold will be described more at length as the description 85 proceeds.

Located transversely of this manifold 8 are the grate bars 10, which as will be seen comprise two series, that is a forward and rearward one, with their adjacent ends abutting.

90 It might be mentioned here that the heating area may be enlarged or decreased, that is before installation, as a manifold may be made to accommodate 16 bars as shown or a 95 lesser or greater number; in other words the operation is the same, it being only necessary to make a larger manifold and the working parts in proportion, and add grate bars if a larger furnace grate is needed.

100 The brick foundation for the grate may be made to suit and the arrangement shown has worked out very nicely in actual practice.

105 Referring now to Figs. 4 to 9, a description of the grate bar 10 will be taken up and a description of one is a description of all, except that the fire bars 11^a which fit in the side grate bars are different, which will be explained later.

110 Looking at Fig. 4 for the moment, it will be seen that the grate bar has two side walls 12 which are inclined inwardly throughout their major part and are thickened slightly at their top, or in other words, at 13. The lower inner surfaces are cut away to form vertical sides as at 14 so that the pivotal bottom 15 may fit snugly therein when the said bottom is in its closed position.

115 Referring to Fig. 6 for the moment it will be seen that a goodly portion of the bottom of the bar 10 is cut away for the reception of the bottom 15, and at one end of the bar is an opening 16 which registers with an opening in the manifold 8, when said bar is in position.

120 It might be mentioned that each of these bars is preferably one casting (as may be seen, Figs. 4 to 7) and at one end of the bar (clearly shown in Fig. 7) is a bearing 130

17 formed open at its top and at the other end a bearing 18 is formed which is circular so that the pintle 19 may be housed in the bearing 18 and the pintle 20 then dropped in the bearing 17, making the bottom easily removable if for any reason desired, but not apt to get out of position in use.

10 The pivotal bottom has two braced fingers 21 formed on its under surface which are slightly spaced near their lower end and having the registering openings 22 so that a rod 23 (Fig. 2) may pass between the fingers 21 and be bolted thereto.

15 Along one edge of the bottom 15 and on the upper surface is the extension bar 24 that extends upwardly a short distance (Fig. 4) and substantially through the inner longitudinal dimension of the grate bar 20 and of course beyond the ends of the pivotal bottom. This extension contacts with the fire bars 11 as will be hereafter explained. When a plurality of these grate bars 10 are set in position as shown in Figs. 1, 2 and 3, 25 the rod 23 is connected through the fingers in all the bars comprising the front series and a similar bar 25 through the fingers on the rearward series (Fig. 3), these two rods being operated by the shaft 26 which 30 extends in front of the grate, by means of the arms 27 and 28 on said shaft 26.

In this manner the pivotal bottom of every grate may be tilted simultaneously both in the front and rearward series.

35 Referring now again to the manifold (Figs. 10 to 16) it is, as before mentioned, provided with a plurality of openings 9 in its upper surface and has a boss or upward extending rim 30 around each opening so that the same will fit snugly into the openings 16 of the said grate bars. This manifold is also preferably a unitary casting.

40 At each end of the manifold on its under side a portion is cut away as at 31 which open portions register with the hollow supports 7, which, as will be remembered, are connected with air ducts 4 and 5.

45 In these supports are also positioned dampers 32 which are operated by the rod 33 also extending out in front of the grate.

50 Two other portions are cut out in the bottom of the manifold as at 34 leaving in reality the three braces or cross pieces 35, one in the center and one near each end. A bearing surface 36 is formed in each of these braces 35 and clamps 36' having bearing surfaces are secured to the braces after the bottoms have been installed. In Fig. 12 only one clamp is shown for the sake of clearness.

55 Supported by these braces are the two pivotal bottoms 38 which are provided with the trunnions 39 fitting within the bearing 36 above described and formed on the lower surfaces of these bottoms 38 are fingers 40

with openings 41, which fingers are similar to the fingers on the bottoms of the grate bars. A handle 42 forked at its one end is bolted to the fingers 40 so that the manifold may also be cleared of any accumulations 70 therein. This bottom is made in two parts so that it does not interfere with the shaft 26.

75 Referring now to Fig. 18, detail views are shown of what I have termed fire bars 11, and it is to be understood that each grate bar has a plurality of these set transversely therein, (see Figs. 1, 3) and that these fire bars are all alike except those disposed in the side grate bars, (as is shown in Fig. 19). 80

These fire bars 11 are unitary castings and are relatively narrow in top plan and near their opposite ends are provided with the lugs 43 which extend outward for a slight distance and also downward as at 44. These lugs 43 are for the purpose of correctly spacing these fire bars when placed in the grate bars, that is with relation to each other, to allow or form spaces for the egress of air furnished by the fan through 85 the manifold into the grate bars. The fire bars present two parallel surfaces one at each end as at 45 so they can rest on the edges of the grate bar, (Fig. 4). They are tapered toward the center, where another 90 surface 46 is provided which may be parallel with their upper surface. Also these bars taper in cross section from their top to their bottom, making a slight reduction 95 in the weight and cost per fire bar. More lugs similar to the ones shown at 43 might be provided if desired or might be differently arranged, the object being to provide certain spaced relationship among the bars.

100 The side bars 11^a (Fig. 19) are somewhat similar in character to those already described, that is they are provided with lugs 48, and also lugs 49, but in this instance one edge or side of the bar 50 is disposed at an obtuse angle to the upper surface of the main portion of the bar; in other words it extends upwardly and above the plane of remaining portions. Also at the other edge of the portion 50 is a lug 51, but in this instance extending 110 down to 52 thus forming a seat for the said bar 11^a. Therefore with this form of side bar spaces are not only provided for the air to be admitted to the fire bed from below the surface but provision is also made to 115 admit air above the surface of the fire bed, thus making a better combustion and allowing oxygen to mix with the gases and thereby burn some of them, which would otherwise go out the chimney in the form of 120 smoke.

125 Referring now to the preferred form of my invention again and to Figs. 1, 2 and 3, it will be seen that in the masonry structure suitable supporting bars as 59 are pro- 130

vided on which the ends of the grate bars rest, the grate bars at the sides having the bars 11^a placed therein and the remaining bars having a plurality of the fire bars 11^b therein.

The shaft 26 is then properly hung from the bearing 60 on the manifold and the similar bearing 60' on the front bar 59 and the rods 23-25 are connected to the fingers on the bottoms of the said grate bars, and the handle 42 is also connected to the bottoms in the manifolds. The draft system, that is, fan, engine ducts, etc., have already been described; also the dampers 32 for regulating the draft.

Now supposing it is desired to rock the bars 11 in the grates, all that is necessary is to operate the shaft 26 and this in turn will move the rods 23 and 25 which in turn moves the bottom in every grate bar and forces the extension 24 of every grate bar bottom against the fire bars 11^b and 11^a. The air will also blow out of the bottom relieving the bars of any accumulation and a few movements of shaft 26 will sufficiently shake the fire. By such an arrangement I have not only produced a forced draft furnace grate but have also produced one wherein the fire may be effectually shaken. Also the said grate bars may be easily cleared by tilting the bottoms and thus allowing the escape of any ashes they may have collected in the same.

Again the separable fire bars are easy and cheap to cast and instead of the necessity of the renewal of an entire grate bar, should the surface become damaged by the heat from any reason, as necessary in former instances, with the present type, it would only be necessary at the most to replace a few of the transversely positioned fire bars 11.

It will thus be seen that I have provided a structure composed of novel grate bars having pivotal bottoms which are so arranged that they contact with fire bars located therein. Also, the fire bars have been so designed that they allow certain spaced relationship for the egress of air and are positioned transversely of the main bars. Also the fire bars 11^a are so shaped that a portion of them extend above the fire level allowing air to be released above the fire, and at the same time being capable of being rocked.

Lastly the complete assembly is shown exposing a grate which may be of any area, and wherein all the grate bars may be cleaned or the fire shaken by a movement of one shaft, and the manifold also cleaned when desired.

From the foregoing it will be seen that my grate is a very practical one and that the parts are relatively cheap to manufacture. Any worn parts may be easily re-

placed and the fire bars will wear out before the grate bars.

Many slight changes as to form, details, sizes, etc., may be made without in any way departing from the spirit and scope of the present invention.

Having thus described my invention what I claim as new and desire to secure by Letters Patent is:

1. A forced draft furnace grate comprising a plurality of hollow grate bars, fire bars located transversely of said grate bars, said grate bars provided with pivotal bottoms, a rod connected with all of the bottoms of said bars for tilting simultaneously the said bottoms and said bottoms rocking the said fire bars located on said grate bars when said bottoms are tilted.

2. In a forced draft furnace grate a plurality of grate bars formed in two series, a manifold for supporting the inner adjacent ends of said grate bars, a plurality of fire bars located on each of said grate bars, said grate bars provided with pivotal bottoms, a rod located under each series of grate bars and each rod connected with the pivotal bottoms of one series for tilting the same, said bottoms respectively provided with extensions thereon for rocking said fire bars when said rods are actuated.

3. A forced draft furnace grate comprising a plurality of hollow grate bars arranged in a front and rearward series, said grate bars having openings in their bottoms, a manifold provided with a plurality of openings for supporting the inner adjacent ends of said grate bars, the openings in the manifold registering with the openings in the bottoms of said grate bars, means for supplying air to said manifold, a rock shaft located transversely of said manifold, two rods connected with said shaft, pivotal bottoms in said grate bars and connected to the two said rods whereby a movement of said rock shaft will simultaneously tilt the bottoms of said grate bars, fire bars located on said grate bars and means on said pivotal bottoms to contact with and rock said fire bars with relation to the said grate bars when said rock shaft is operated.

4. A forced draft furnace grate comprising a plurality of intermediate and end grate bars all of said bars provided with pivotal bottoms, a main rock shaft, means connected with said pivotal bottoms and said rock shaft to tilt all of said bottoms when said rock shaft is operated, spaced fire bars located on said grate bars, the fire bars on said end grate bars extending above the normal level of the remainder of said fire bars, the said pivotal bottoms respectively provided with extensions thereon for rocking the fire bars located on both the intermediate and the end grate bars.

5. A forced draft furnace grate comprising

ing a plurality of hollow grate bars, fire bars located on said grate bars, the fire bars located on the end grate bars extending above the normal level of the remainder of 5 said fire bars, all of said grate bars provided with pivotal bottoms and means for rocking said pivotal bottoms, each of said pivotal bottoms provided on its edge with an upwardly extending lug to thereby rock the 10 respective said fire bars in said grate bars and a manifold also provided with a pivotal bottom and means for tilting the same.

6. A forced draft furnace grate comprising in part a hollow grate bar, fire bars located on said grate bar, said grate bar having inclined side walls and a pivotal bottom located therein, said bottom provided with a downwardly extending finger adapted to receive a tilting member and an upwardly 20 extending lug, said lug adapted to contact with and rock said fire bars when said bottom is tilted.

7. A forced draft furnace grate comprising in part a hollow grate bar, and a plurality 25 of transversely disposed fire bars in said grate bar and a pivotal bottom in said grate bar provided with an upward extension adapted to rock said transversely extending fire bars when said bottom is tilted.

30 8. A forced draft furnace grate comprising in part a hollow grate bar, a plurality of fire bars resting on said grate bar and said fire bars provided with lugs to correctly space one fire bar with relation to another, 35 a pivotal bottom in said grate bar provided with an upward extension thereon, said extension extending substantially throughout the inner length of said grate bar, and raising the ends of all of said fire bars when 40 said bottom is sufficiently tilted.

9. A forced draft furnace grate comprising in part a hollow grate bar provided with

a pivotal bottom having an upward extension thereon, said grate bar being open in its top, a plurality of fire bars provided with 45 lugs on their opposite sides to correctly space one fire bar from another when placed in position, said fire bars extending downwardly into said grate bar and being supported thereon, a pivotal bottom in said 50 grate bar provided with means for contacting with and rocking the said fire bars when said bottom is sufficiently tilted.

10. A forced draft furnace grate comprising in part a grate bar having end and side 55 walls open at its top, a plurality of fire bars having cut out portions at their under edges for resting on the side walls of said grate bar, a pivotal bottom in said grate bar, said fire bars provided with means for spacing 60 one from another, said fire bars having tapered lower portions and said pivotal bottom having formed thereon means for contacting with the lowermost surface of said fire bars to raise the ends of the fire bars 65 and thereby rock the same.

11. A forced draft furnace grate comprising in part a hollow grate bar having end and side walls and open at its top, the side walls being thickest at their upper portion 70 and tapering at their lowest edges, a pivotal bottom set in said grate bar adapted to fit snugly when closed, said pivotal bottom provided with a bar extending substantially throughout the inner longitudinal dimension 75 of said grate bar, said pivotal bottom being provided with depending fingers on the bottom thereof, means for supporting said pivotal bottom and a plurality of fire bars located on said grate bar and adapted to be 80 rocked by the said longitudinally extending bar when the bottom is tilted.

In testimony whereof I affix my signature.
LEE HOWARD SIMMONS.
